US00D609707S

(12) **United States Design Patent**
Lee

(10) **Patent No.:** US D609,707 S
(45) **Date of Patent:** ** Feb. 9, 2010

(54) **DOCKING STATION FOR ELECTRONIC DEVICE**

(75) Inventor: **Chuen-Wah Lee**, Hong Kong (CN)

(73) Assignee: **Clipsal Australia Pty Limited**, Sydney (AU)

(**) Term: **14 Years**

(21) Appl. No.: **29/314,353**

(22) Filed: **Mar. 24, 2009**

(30) **Foreign Application Priority Data**

Sep. 25, 2008 (HK) 0802352

(51) **LOC (9) Cl.** 14-02

(52) **U.S. Cl.** D14/434

(58) **Field of Classification Search** D14/432-434, D14/314, 204, 420, 421, 447, 217; D13/108, D13/146; D23/314, 328; 248/346.03; 361/679.41, 361/679.31, 379.32, 679.4, 679.43; 70/58; D21/333; 320/112, 109; 348/375; 381/333

(57) **CLAIM**

The ornamental design for a docking station for electronic device, as shown and described.

DESCRIPTION

FIG. 1 is a front perspective view of a docking station for electronic device showing my new design;

FIG. 2 is a rear perspective view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a right side elevational view thereof; and,

FIG. 8 is a left side elevational view thereof.
